(57) **CLAIM**

The ornamental design for a flat lamp, as shown and described.

DESCRIPTION

FIG. 1 is a front perspective view of a flat lamp, showing our new design;

FIG. 2 is a bottom, rear, right side perspective view thereof; FIG. 3 is an exploded view of the flat lamp shown in FIG. 2;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof; and,

FIG. 10 is an enlarged view of a portion labelled **10** in FIG. 2.

The broken lines in the drawings depict portions of the flat lamp that form no part of the claimed design.

The dash dot dash lines in FIG. 2 and FIG. 10 are for the purpose of depicting the cut line of the enlarged view and form no part of the claim.

1 Claim, 10 Drawing Sheets
